UNITED STATES PATENT OFFICE.

EGBERT VON LEPEL, OF BERLIN-WILMERSDORF, GERMANY.

METHOD OF PRODUCING ELECTRICAL OSCILLATIONS.

1,168,837.

Specification of Letters Patent.

Patented Jan. 18, 1916.

Application filed December 29, 1914. Serial No. 879,587.

To all whom it may concern:

Be it known that I, EGBERT VON LEPEL, a subject of the King of Prussia, residing at Berlin-Wilmersdorf, in the Empire of Germany, have invented new and useful Improvements in Methods of Producing Electrical Oscillations, of which the following is a specification.

It is known to produce electrical oscillations of high frequency by periodically discharging a condenser over spark gaps. The periodical discharge may be effected either directly over the spark gap, or indirectly by charging and discharging, or changing the charge, of a blocking condenser by means of rotating or vibrating commutating devices, or artificial ignition.

Figures 1 to 5, inclusive, diagrammatically illustrate different systems for producing electrical oscillations of high frequency by periodically discharging a condenser over spark gaps; Fig. 6 diagrammatically illustrates a system embodying my invention for producing electrical oscillations of high frequency; Figs. 7 and 8 are curves illustrating the theory of operation of the systems shown in Figs. 1 to 5; Fig. 9 is a curve illustrating the theory of operation of the system embodying the present invention; Figs. 9^a and 9^b represent separately the course of the current in the condenser branch of the circuit and in the spark gap branch of the circuit of Fig. 6, when the spark gaps 4 produce a quenching effect; Fig. 10 is a curve illustrating the theory of operation of the system when the supply current is maintained absolutely constant; Figs. 10^a and 10^b separately illustrate the course of the current in the condenser branch of the circuit and in the commutator wheel branch of the circuit of Fig. 6; Figs. 11 and 12 illustrate portions of rotating commutators for charging and discharging condensers; and Fig. 13 diagrammatically illustrates a system embodying my invention and in which two pairs of condensers are employed.

Various methods are illustrated in Figs. 1 to 5 of the accompanying drawings.

In Fig. 1 the condenser 1 which is fed from the direct current source 2 becomes discharged over the spark gap 4 in an oscillatory circuit on every half turn of the rotating blocking condenser 3, in connection with which a change of charge of the blocking condenser 3 takes place each time. The coupling coil 5 transmits the energy of the high

frequency oscillations thus produced to the circuit of the antenna. If a feeding current of high potential is used additional spark gaps 8 may be inserted in a number corresponding to the potential of the current. The object of the resistance 6 and the self-induction 7 will be explained later on.

In Fig. 2 a similar arrangement is shown except that the blocking condenser 3 is, by means of the rotating commutator 9, alternately charged and discharged whereas in Fig. 1 the charge is periodically changed.

With the method illustrated in Fig. 3 the charge of the blocking condenser 3 is periodically changed but this change is initiated by means of artificial ignition, instead of by means of a rotating commutator. For this purpose the pairs of spark gaps 10 and 11 are alternately bridged, in a well known manner, by artificial ignition whereby the blocking condenser 3 is oscillatorily commutated in constantly changing direction.

With the method illustrated in Fig. 4 the blocking condenser is dispensed with; a rapidly rotating short circuiting wheel 9 is used instead. Since in this case the discharging current and the energy supplied from the current source 2 are not blocked the danger that arc formation will occur by reason of the short-circuiting of the current source must be met by a rapid rotation of the short circuiting wheel 9. Another measure (i. e. tuning the feeding current circuit) is frequently applied for the same purpose, and will be described later on.

In Fig. 5 stationary quenching spark gaps 12 (according to v. Lepel) are used in place of the rotating short circuiting wheel 9. Herewith, the almost continual oscillations of this arrangement may be, for telephonic transmission, rhythmically subdivided by means of a tuning circuit 15. The effect of avoiding arc formation, obtained in Fig. 4 by rapid rotation of the electrodes, is secured in the method illustrated in Fig. 5 by means of Lepel's quenching spark gaps. However, it is well to point out that arc formation is more perfectly and in quite a different manner prevented by means of quenching spark gaps than by ruptured spark gaps. While the rupture of the arc even with rapid rotation of the electrodes, takes place but slowly in comparison to the duration of the spark, and not before the oscillations have long since died away, the use of quenching spark gaps insures an interruption of the jumping

spark after the first half surge, that is, much quicker and more regularly.

With the methods thus described it is often advantageous to insert choking coils 6 (see Figs. 1 to 5) into the feeding circuit for limiting and damping the supply current. Where blocking condensers are wanting (see Figs. 4, 5) the arrangement of such choking coils, or automatic maximum interrupters, is advisable in order to prevent short circuits. Frequently, besides choking coils 6, small self-inductances 7 (see Figs. 1 to 5) have been proposed and used for the supply circuit of the described arrangements; and this for two different reasons: Firstly, to protect the direct current source from returning high frequency oscillations. Practical experience has shown that air choking coils having about 100 windings serve this purpose. In many cases an additional condenser is connected in parallel to the source of current to farther protect the latter. Secondly, in some cases a tuning of the supply circuit is aspired to by means of the self-induction coils. The supply current flowing through this circuit is, with the described arrangements, not at all constant. The behavior of this current will be followed up in connection with the method illustrated in Fig. 1 and with reference to Fig. 7. The direct current potential E, hereinafter briefly called supply potential, applies at first to the condenser 1 as well. At the moment the blocking condensers 3 are oscillatorily commutated, the potential e of the condensers 1 dwindles oscillatorily away from the value E to assume, after the oscillatory equalization, a correspondingly lower value V. This decrease of potential effected by the spark is indicated in the diagram of Fig. 7 by means of the heavy line 16—17. The charging of condenser 1 now follows: if

$$w^2 < \frac{4L}{a}$$

which is mostly the case in practical working arrangements, this charging proceeds oscillatorily, w in the foregoing formula being equal to 2π times the frequency of the electro-motive force of the supply circuit, L representing the inductance of the circuit, and a representing the capacity of the condenser. The curved line 16, 17, e ; 16, 17 e , and so on, is a representation of the potential e prevailing at the condenser 1, while the feeding current follows the dotted line i . Now, since with a complete oscillatory charge of a condenser 50 per cent. of the supplied energy is lost through production of heat, a special advantage is secured by not permitting the upward oscillating energy that passes during the first $\frac{1}{4}$ wave length far beyond the supply potential E (in fact it increases to the value $2E - V$) to die away, but to start the next spark ignition in the maximum

point 18 of the first half oscillation. Thereby the loss of half the energy is prevented and the advantage is secured that one is enabled to work, at the moment of the ignition, with a condenser potential equal to $2E - V$. This state is easily obtained by tuning the supply circuit by means of self-induction coils 7 in such a way that the increase of the potential e from the value E to the value $2E - V$ concurs with the rhythm of the commutations, that is, the spark series. The potential e and the supply current i would then follow the lines shown in Fig. 8. If no blocking condenser is used, as with the arrangement illustrated in Fig. 4, such a tuning secures the further advantage that the supply current i passes zero at the moment of the ignition, hence, it is an advantageous measure for averting the above mentioned danger of arc formation. This tuning system is charged with various defects, principally because it is not always easy to obtain the proper tuning and to prove its existence unobjectionable. Moreover, since the ignitions are to occur as accurately as possible, in the maximum point 18 of the value of the potential, and since an occasional irregularity of a single ignition will affect the subsequent ignitions and will in consequence disturb the regularity of the spark series, the tuned state is rather sensitive to disturbing influences, to which defects must be added the objectionable necessity of altering the tuning of the supply circuit on any occurring alteration in the rhythm of the spark series.

Nicola Tesla in his British Patent 20981 A. D. 1896 and in his U. S. Patent 577670 of 1897 has described arrangements for the production of oscillations of high frequency which arrangements are in some respects similar to the arrangement shown in Fig. 7 except for the feeding of the current to the commutating wheel 9 which is done by means of brushes instead of spark gaps; furthermore the blocking condenser is absent. Tesla too inserts into the supply circuit self-induction coils, of a higher order than those of the above mentioned coils that have a self-induction large enough to keep the current i in the supply circuit entirely or approximately constant for the length of the interval T between two oscillation impulses. In the following these coils will briefly be called inertia-coils. The electrical conditions of this method are explained in the diagram Fig. 10; for the sake of simplicity it is supposed that ideal inertia-coils (i. e. infinitely large ones with regard to the rhythm of the oscillation impulses) are arranged which keep the supply current i absolutely constant for the length of the interval between two oscillation impulses. It may be seen that in this case too the tension e of the condenser 1 that is being

charged by the feeding current i kept constant increases lineally, in the way graphically explained by the straight tension lines 20, 19 in Fig. 10. The current i flowing in the feeding circuit, is represented by the straight horizontal line i . Since a blocking condenser is absent in Tesla's arrangement the condenser tension A, in the short-circuit position sinks from the initial value A to zero after all of the oscillation surges have died away; this phenomenon is indicated by the vertical lines 19—17. At the same time the current i , kept constant by means of the inertia-coil, takes its course over the short circuiting wheel 9 and there remains constant until disconnected by rupture. During this time (17—20) the condenser 1 being short-circuited is without tension, hence, the tension curve e coincides with the zero line during the interval 17—20. After the rupture, the current i , still kept constant, may only go to the condenser which now is not any longer short-circuited and which becomes recharged by the current i . It will be seen that the current in the feeding circuit serves alternately as charging current (from 20—17) and as short-circuit current (from 17—20).

For the sake of completeness, the current diagrams of the condenser branch (*i. e.* the charging current) and of the commutator wheel branch (*i. e.* the short-circuit current) are separately illustrated in Figs. 10^a and 10^b. Both together represent the constant current i flowing through the supply circuits.

Since the inertia-coil has only a regulating effect and therefore gives off always so much electrical energy as it had magnetically stored previously, the current values and tension values will always adjust themselves in such a way that the lined rhombical surface 23, 17, 20, 24, representing the energy stored, equals the lined triangular surface 24, 19, 23 representing the energy given off. From this it follows that the initial tension A of the condenser 1 at the moment of ignition exceeds the feeding tension E both before and after the oscillatory equalization has taken place. This effect would be very advantageous if it were not accompanied by the short circuit-currents illustrated separately in Fig. 10^b. Since the inertia-coil keeps the current in the feeding circuit constant the short circuit-currents are to be interrupted in their full intensity whereby, naturally, violent and dangerous rupture arcs occur. As the rupture phenomenon, in addition, is very irregular on account of the sensitivity of the arc, disturbing fluctuations will occur in the tension line and, hence, in the rhythm as well as in the intensity of the impulse. These disadvantages weigh so heavily technically that this method has never been

worked in actual practice so far as applicant is aware. Moreover, the defects of tuning, as explained above, are put up with in order to have to break but weak currents at the moment of the short-circuiting position. As 70 is already said, the requirement of high regularity has to be foregone. However, according to this invention a special advantage may be obtained if through the use of suitable spark gaps each spark is extinguished immediately after the first half of its surge and if the supply current which on account of the extinction of the spark goes solely to the condenser 1 is kept entirely or approximately constant by means of a 80 self-induction of sufficiently high order for intervals of the order of the spark series, so that by the combined effect of spark extinction and the keeping constant of the supply current the tension of the condenser in the 85 moment of the ignition in connection with any spark rhythm is increased so much or approximately so much above the feeding tension as it will go down below the same after the oscillatory equalization has taken 90 place.

By combining quenching spark gaps and inertia-coils (the latter are indicated in Fig. 6 as large iron-enclosed self-induction coils 14 of the shape of normal transformers) the 95 defects of the tuning method are not only got rid of, since now any tuning of the supply circuit may be dispensed with, but the very detrimental, and in practical working absolutely impeding, short-circuits are 100 avoided.

To the arrangement shown in Fig. 6 which, however, corresponds to the new method only if the spark gaps 4 produce a quenching effect, the diagram of Fig. 9 105 would correspond. The diagrams Fig. 9^a and Fig. 9^b represent separately the course of the currents in the condenser branch and in the spark gap branch, in the same way as do the diagrams Fig. 10^a and Fig. 10^b. Since 110 a blocking condenser 3 is provided, the condenser tension e consequently will not decrease to zero after the oscillatory equalization, but only drops to the value of the equalization tension V. The difference obtaining on a comparison with Fig. 10 and which forms a feature of this invention is at once apparent: Points 17 and 20 (Fig. 10) will in this case join in the single point 17 (Fig. 9), the charging current (Fig. 9^a) 120 remains constant, the infinitesimally small duration of time occupied by the first half surge not considered, and the short circuit currents following the oscillatory equalization, and which are detrimental in several 125 respects, do not occur.

While with the tuning method the intensity of the charging current i and its sinusoidal path (see Fig. 8) is essentially influenced by the self-induction L of the sup- 130

ply current circuit and with Tesla's method, by the duration of the short-circuit currents, so that the current intensity is in a state of stable equilibrium with regard to the self-induction or the short-circuit currents; with the novel method the intensity of the feeding current i is only depending upon the number of discharges, and is in condition of indifferent equilibrium with regard to the self-induction of the inert coil (which keeps the current constant for the space of time of the series of sparks but does not influence it in its absolute value beyond this). For instance, if the number, or the quantity, of the discharges is slowly increased, the intensity of the feeding current i will increase (like a slowly increasing direct current). Condenser 1 works in combination with the rotating blocking condenser under the influence of the inertia-coil apparently like a resistance situated in the feeding circuit. The provision of the periodically commutating blocking condenser has an effect upon the continuous current circuit like a stationary condenser in an alternating current circuit: forming an apparent resistance, *i. e.* a current restricting resistance.

Although the inertia-coils do not influence the feeding current i in its absolute quantity they still suppress any fluctuation of current within the interval of two succeeding sparks, with the result that the current shows a constant medium value. Likewise, for the same physical reason, the tension of the condenser 1, at the moment of ignition, will under the influence of the inertia-coil and the extinction effort of the spark gaps lie as much, or approximately as much, above the feeding tension E as below the latter after the oscillatory equalization. Geometrically considered, in this case, too, the shaded triangle 23, 17, 24 must equal in surface the triangle 24, 19, 23. Hence, with combined application of inertia-coils and quenching spark gaps the feeding tension will be

$$E = \frac{A + V}{2};$$

50 therefore

$$A = 2E - V.$$

Furthermore, it may be generally stated that with the condenser 3 connected in parallel to the condenser 1, the equalization tension equals

$$V = \frac{Aa + Bb}{a + b};$$

or

$$60 \quad V(a+b) = Aa + Bb$$

wherein V represents the tension of the condenser 1 after the oscillatory equalization has taken place (equalizing tension), A represents the tension of condenser 1 at the

moment of ignition, B represents the tension which blocking condenser 3 offers the condenser 1, a represents the capacity of condenser 1 and b represents the capacity of the blocking condenser 3.

If with the new method, the periodical discharge of condenser 1 is started by commutating blocking condenser 3, then,

$$E = -V$$

for blocking condenser 3 offers the inverted equalization tension V toward condenser 1. The following mathematical equalizations will apply:

$$V(a+b) = Aa + Bb = 2Ea - V(a+b)$$

wherefrom the equalization tension may be obtained as follows:

$$V = \frac{a}{Ea + b}$$

On giving, for instance, both condensers 1 and 3 an equal capacity $a = b$, the following values are obtained:

$$V = \frac{1}{2}E$$

$$A = \frac{1}{2}E$$

$$Z = A - B = 2E$$

wherein Z represents the total tension of ignition.

The energy taken from condenser 1 at each discharge amounts to

$$(A^2 - V^2) \frac{a}{2} = \left(\frac{9}{4}E^2 - \frac{1}{4}E^2 \right) \frac{a}{2} = E^2 a \quad 100$$

If T is the time of charging, the energy conducted into condenser 1 at each discharge amounts to

$$iET = E^2 a$$

which yields the feeding current as follows

$$i = \frac{Ea}{T}$$

If the periodical discharge of condenser 1 is started by charging and discharging blocking condenser 3, then,

$$B = 0$$

and for the equalization tension the value

$$V = E \frac{2a}{2a + b}$$

is obtained.

If $a = b$ the following values result:

$$V = 2/3E$$

$$A = 4/3E$$

$$Z = 4/3E$$

$$i = 2/3 \frac{Ea}{T} \quad 125$$

Z representing the total ignition tension. In a similar manner the proper values for V , A , Z and i may be determined if the

periodic discharge of condenser 1 is not accomplished by a change of charge, or by charging and discharging the blocking condenser 3, but if started by any of the methods described in the introduction, for instance the methods according to Figs. 4 and 5. The system 13 indicated in Fig. 6 on the right hand side of the dash and dotted line, which accords with the corresponding part 10 of Fig. 1, is, then, replaced by the corresponding parts of Figs. 2 to 5; however, in this connection it is essential that the spark gaps 4, or 10, 11 respectively have quenching effects.

15 What distinguishes the novel method essentially from the known arrangements, is the feature of applying inertia-coils and quenching spark gaps combined. From the effect of this combination as above described 20 in detail it follows that with the novel method the ohmic resistance 6 may be substantially smaller, or may be dispensed with entirely, as in Fig. 6. For, since the system 13, under the influence of the inertia-coils 25 and the quenching spark-gaps, works apparently like a resistance, the effect of the resistance 6 may be obtained, entirely or partly, by means of this system; which is very advantageous because the loss of energy 30 entailed by the use of the resistance is completely or partly avoided. A protecting condenser connected in parallel to the source of current is not required with this system. Of course, the Figs. 1 to 5 do not exhaust all 35 possibilities. For instance the commutator of the rotating blocking condenser 3 may be combined with artificial ignition; by means of this artificial ignition the jump of the spark will then be started when the distance 40 of the electrodes has reached its minimum whereby a very accurate series of sparks is secured.

If the rhythm of the spark series is accelerated or delayed, this will entail an increase 45 or a decrease of the intensity of the feeding current, as has been mathematically shown above. This increase or decrease of the currents will suffer, on account of the inertia-coils, a slight delay in comparison 50 with the speed governing the alteration of the rhythm. Since a like delay occurs also with the ignition tension, an after ignition, or a prior ignition, results therefrom at the 55 rotating electrodes, which may give rise to irregularities if the alteration happens comparatively quickly. It may thus happen that the ignition which normally starts at the point 30 of the toothed electrode 29 (Fig. 11), occurs during the acceleration at 60 31 or 32, or during the delay at 33 or 34. The electrode 28 is, then, at the moment of the ignition, opposite of a sharp edge of the toothed electrode 29, which position might easily favor arc formation, since experience 65 proves that sharp edged or pointed elec-

trodes on account of the high local heat production favor the transition of a spark into an arc. If, however, two flat electrodes are opposing each other at so small a distance that they work as quenching spark 70 gaps, on suddenly increasing the distance the spark will be interrupted. Therefore, in some cases it is expedient not to give the commutating electrodes sharp edged sides running parallel to the axis of rotation as 75 shown in Fig. 11 but to choose electrodes with slightly undulated surfaces as illustrated in Fig. 12.

Whether the condition of a constant feeding current so essential for the new method 80 is attained can only be ascertained by the insertion into the feeding circuit of measuring instruments adapted for a continuous and for an alternating current. Since the continuous current instrument will indicate 85 the mean value of the instantaneous current intensity, the alternating current instrument, however, the square root of the mean value of the square of the currents, both instruments, if the feeding current takes a 90 sinusoidal or otherwise undulating path, will give dissimilar indications, whereas they will show the same reading only if the feeding current is absolutely constant. It is, however, simpler to measure the sec- 95 ondary tension of an auxiliary coil placed, for that purpose, around the iron-core of the inertia-coil. This secondary tension will equal zero, or will approximate to zero, if the feeding current is perfectly or ap- 100 proximately constant.

Whether the equally important quenching effect exists may be inferred, in a well known manner, from the degree of coupling which corresponds to the best effect, and from the 105 produced oscillations having a single resonance maximum. After some experience the existence of the quenching effect may be recognized from the character of the sparks and from the exact and arc-free operation. 110 Furthermore, for high tensions, the described method may be extended to comprise two, or more, condensers instead of one, in such a way that condenser 1 is charged in a parallel system but is dis- 115 charged over the blocking condensers connected in series.

In Fig. 13, by way of example, an arrangement for two pairs of condensers is shown in accordance with this principle. 120 Of course, in a similar manner, an arrangement may be made for three, or more, pairs of condensers. Fig. 13 directly shows that through the rotation of the synchronously revolving commutating devices (which may be mounted on a common shaft) the condensers 1 are charged in parallel at the frequency of the series of sparks over the inertia-coils 15, while they are discharged in series over the blocking condensers. In this 130

way, the total ignition tension in the oscillatory circuit may, if m -pairs of condensers are arranged, be increased to the m -fold value of the single arrangement, whereby, if the total capacity remains equal (that is, if the single condensers are enlarged m -fold) the oscillating energy increases proportionally to m^2 .

Although Braun proposed a similar mode of connection for alternating current, the subject of the present application essentially and advantageously distinguishes itself from Braun's arrangement by the fact that in the discharge position there are not only inserted one or a plurality of spark gaps between each two charging condensers (1_1 and 1_2) connected in series, but also a blocking condenser 3_1 , whereby the danger of a short circuit (which the diagram indicates) is entirely obviated, whereas Braun proposes, for the same purpose, the use of resistances in the feeding line.

What I claim is:—

1. The method of producing electric oscillations of high frequency which comprises charging a condenser from a source of current, establishing a spark discharge across a suitable spark gap by periodically discharging the condenser over said spark gap, and extinguishing each spark after the first half oscillation or after the first train of oscillations of the discharge energy, feeding during the spark extinction the charging current solely to the condenser and maintaining said current at an approximately constant strength so that the combined effect of the spark extinction and substantially constant strength of the charging current will render the potential of the condenser, with any frequency of sparks, as much above the potential of the charging source at the moment of discharge as it is below after the discharge.

2. The method of producing electric oscillations of high frequency which comprises charging a condenser from a source of direct current and through suitable self inductances, establishing a spark discharge across a quenched spark gap by periodically discharging the condenser over said spark gap, and extinguishing each spark after the first half oscillation or after the first train of oscillations of the discharge energy, feeding the charging current during the spark extinction solely to the condenser and maintaining said current at an approximately constant strength by the self inductance in the supply circuit so that the combined effect of the spark extinction and substantially constant strength of the charging current will render the potential of the condenser, with any frequency of sparks, as much above the potential of the charging source at the moment of discharge as it is below after the discharge.

3. The method of producing electric oscillations of high frequency which comprises charging a condenser from a source of direct current which current is supplied to said condenser through inertia self induction coils, establishing a spark discharge across a quenched spark gap by periodically discharging the condenser over said spark gap, extinguishing each spark after the first half oscillation or after the first train of oscillations of the discharge energy, feeding the charging current during the spark extinction solely to the condenser and maintaining said current at an approximately constant strength so that the combined effect of the spark extinction and substantially constant strength of the charging current will render the potential of the condenser, with any frequency of sparks, as much above the potential of the charging source at the moment of discharge as it is below after the discharge.

4. The method of producing electric oscillations of high frequency which comprises charging a condenser from a source of direct current and establishing a spark discharge by periodically discharging said condenser through an oscillation circuit containing a blocking condenser and a spark gap, and extinguishing each spark after the first half oscillation or after the first train of oscillations of the discharge energy, the current charging said condenser being maintained at substantially constant strength during the period between successive spark discharges.

5. The method of producing electric oscillations of high frequency which comprises charging a plurality of condensers in parallel, from a direct current supply and through suitable self-induction coils, establishing spark discharges across suitable spark gaps by periodically discharging said condensers in series over said spark gaps, extinguishing each spark after the first half oscillation or after the first train of oscillations of the discharge energy, feeding the charging current during the spark extinction solely to the charging condensers and maintaining said current at an approximately constant strength by said self-induction coils during the period between successive spark discharges, so that by the combined effect of the spark extinction and the substantially constant strength of the charging current, the potential of the charging condensers, with any frequency of sparks, will be as much above the potential of the charging source at the moment of discharge as it is below after the discharge.

6. In an apparatus for producing high frequency oscillations, the combination of a source of direct current, an oscillation circuit including a spark gap, a charging condenser connected to said source of direct

- current and to said oscillation circuit, means for maintaining the strength of the charging current substantially constant for the interval between two oscillation impulses, 5 and means for periodically discharging said charging condenser over said spark gap and extinguishing each spark after the first half oscillation or after the first train of oscillations of the discharge energy, the arrangement being such that during the spark extinction the charging current feeds solely to the charging condenser and is maintained at an approximately constant strength during the period between the successive spark 10 discharges whereby by the combined effect of the spark extinction and by the substantially constant strength of the charging current, the potential of the charging condensers with any frequency of sparks will 15 be as much above the potential of the charging source at the moment of discharge as it is below after the discharge.
7. In apparatus for producing high frequency oscillations, the combination of a source of direct current, an oscillation circuit including a spark gap and a blocking condenser, a charging condenser connected to said source of direct current and to said oscillation circuit, self-induction coils in the 20 connections between said charging condenser and source of current, said coils being of sufficient size to maintain the current of the supply circuit constant for the length of the interval between two oscillation impulses, and means for periodically discharging said discharging condenser over said spark gap and blocking condenser and extinguishing each spark after the first half oscillation or after the first train of oscillations of the discharge energy, whereby during the spark extinction the charging current feeds solely to the charging condenser and is maintained at an approximately constant strength during the period between the successive spark discharges by said self-induction in the supply circuit so that by the combined effect of the spark extinction and the substantially constant strength of the charging current the potential of the charging condenser, with any frequency of sparks, will be as much above the potential of the charging current at the moment of discharge as it is below after the discharge.
8. In an apparatus for producing high frequency oscillations, the combination of a source of direct current, an oscillation circuit including a spark gap and a blocking condenser, a charging condenser connected to said source of direct current and to said oscillation circuit, inertia coils in the connections between said charging condenser and source of current, said coils being of such size as to maintain the strength of the current of the supply circuit absolutely constant for the length of the interval between two oscillation impulses, and means for periodically discharging said charging condenser over said spark gap and extinguishing each spark after the first half oscillation or after the first train of oscillations of the discharge energy, whereby during the spark extinction the charging current feeds solely to the charging condenser and is maintained at an approximately constant strength during the period between successive spark discharges by said inertia coils in the supply circuit so that by the combined effect of the spark extinction and the substantially constant strength of the charging current the potential of the charging condenser, with any frequency of sparks, will be as much above the potential of the charging current at the moment of discharge as it is below after the discharge.
9. In an apparatus for producing electric oscillations of high frequency, the combination of a source of current, a plurality of charging condensers connected in parallel to said source of current, an oscillation circuit connected with said charging condensers and including a blocking condenser, and means whereby the charging condensers may be discharged over the blocking condenser in series.
10. In an apparatus for producing electric oscillations of high frequency, the combination of a source of direct current, a plurality of charging condensers connected in parallel to said source of current, an oscillation circuit connected with said charging condensers and including a plurality of blocking condensers and spark gaps, and means whereby the charging condensers may be discharged over the blocking condensers and spark gaps in series.
